UNITED STATES PATENT OFFICE.

THOMAS OCTAVE MURDOCK SOPWITH, OF KINGSTON-UPON-THAMES, ENGLAND.

ADJUSTABLE SEAT FOR GUNNERS IN ARMED AEROPLANES AND THE LIKE.

1,275,624.

Specification of Letters Patent. Patented Aug. 13, 1918.

Application filed August 14, 1917. Serial No. 186,233.

To all whom it may concern:

Be it known that I, THOMAS OCTAVE MURDOCK SOPWITH, commonly known as THOMAS SOPWITH, a subject of the King of Great Britain and Ireland, residing at Canbury Park Road, Kingston-upon-Thames, in the county of Surrey, England, have invented certain new and useful Improvements in Adjustable Seats for Gunners in Armed Aeroplanes and the like, of which the following is a specification.

This invention relates to adjustable seats for gunners in armed aeroplanes and the like and consists of an improved method of 15 and means for automatically locking the adjustable seat in any position the gunner may desire.

In order that the gunner can adapt his 20 position to train the gun in the most satisfactory manner within the confined space available in an aeroplane or the like, the seat is eccentrically mounted on a pivot carried by a suitable fixed stand and a locking device is provided for locking the seat to the 25 stand, said device automatically coming into operation when the seat is occupied and becoming automatically inoperative when the seat is relieved of the weight of the occupant.

30 In order that my invention may be fully understood, I will more particularly describe it, making reference to the accompanying drawing in which:—

Figure 1 is a view in side elevation partly 35 in section showing the seat and its stand, the locking device being in its inoperative position, and

Fig. 2 is a view in plan thereof.

In both views similar parts are marked 40 with like letters of reference.

The seat *a*, which may be of any suitable construction and is preferably of circular shape, has a plate *b* fixed eccentrically on its under side. This plate carries a pin *c* 45 which fits in a socket *d* carried by a stand *e* which may conveniently comprise a plurality of legs as shown in the accompanying drawing. On the upper part of the socket *d* or on a plate or flange *d*¹ thereon and on the opposite face of the plate *b* mounted on the seat *a* are serrations *f* which when they are engaged prevent the rotation of the seat *a* relative to the stand *e* and thereby lock the seat in position. These serrations 55 are normally kept out of engagement by a spring *h* located in the bottom of the

socket *d* and operating between same and the bottom of the pin *c* to lift the pin and therefore the seat. To limit the action of the spring *h* and confine the seat *a* to the 60 stand *e* a reduced extension *c*¹ of the pin *c* passes through a hole in the bottom of the socket *d* and is provided on its free end with a collar *c*² which may conveniently take the form of a nut as shown in the accompanying 65 drawing.

It will be appreciated that when the weight of the gunner is on the seat the serrations *f* are in engagement and the seat is locked against rotation and that when the 70 gunner desires to alter the position of the seat all he has to do is to relieve the seat of his weight when the seat becomes free and can be turned in any desired direction, and that it will become locked again as soon as 75 the gunner returns his weight to the seat.

What I claim as my invention, and desire to secure by Letters Patent is:—

1. A seat for gunners in aeroplanes and the like comprising a seat, an eccentrically 80 arranged pin mounted on the under side of said seat, a stand for said seat, a socket carried by said stand and adapted to receive the pin carried by the seat, a vertically engaging locking device between said pin and 85 said stand, and a spring operating between said pin and said socket to keep said locking device inoperative.

2. A seat for gunners in aeroplanes and the like comprising a seat, an eccentrically 90 arranged plate mounted on the under side of said seat, a pin carried by said plate, a stand for said seat, a socket carried by said stand and adapted to receive the pin carried by the seat, a locking device consisting of a 95 series of serrations on the plate carrying the pivotal pin and a series of serrations on the upper face of the socket in which said pin works, and a spring operating between said pin and said socket to keep said locking 100 device inoperative.

3. In a seat for a gunner in an aeroplane or the like, the combination with the seat, of a plate fixed eccentrically on the under side of said seat, of a pin carried by said plate, 105 of a stand adapted to be fixed to the aeroplane or the like, of a socket carried by said stand and adapted to receive said pin, of a series of serrations on the plate carrying the pivotal pin, of a plate or flange on the upper end of said socket, of a series of serrations in said plate or flange, and of a spring 110

acting between the socket and the pin mounted in it as set forth.

4. In a seat for a gunner in an aeroplane or the like, the combination of a seat *a*, of a plate *b* fixed eccentrically on the under side of said seat, of a pin *c* carried by said plate, of a stand *e* adapted to be fixed to the aeroplane or the like, of a socket *d* carried by said stand and adapted to receive the pin *c*,
10 of a series of serrations *f* on the plate on

the seat, of a series of similar serrations on the socket carried by the stand, of a reduced extension *c*¹ of the pin *c* passing through the bottom of the socket *d*, of a collar or enlargement *c*² on said extension exterior to the 15 socket *d*, and of a spring *h* acting between the socket *d* and the pin *c*.

In testimony whereof I have signed my name.

THOMAS OCTAVE MURDOCK SOPWITH.
